UNITED STATES PATENT OFFICE.

HUBERT RICHMOND AND CARL E. BARBER, OF MEMPHIS, TENNESSEE; SAID RICHMOND
ASSIGNOR TO SAID BARBER.

AMUSEMENT CYCLE-GLOBE.

1,027,069.

Specification of Letters Patent.

Patented May 21, 1912.

Application filed March 1, 1912. Serial No. 680,918.

To all whom it may concern:

Be it known that we, HUBERT RICHMOND and CARL E. BARBER, citizens of the United States, residing at Memphis, in the county 5 of Shelby and State of Tennessee, have invented new and useful Improvements in Amusement Cycle-Globes, of which the following is a specification.

This invention relates to amusement devices known as "bicycle-whirls" for use in expert bicycle or motor-cycle riding.

One object of the invention is to provide a hollow woven wire globe having a skeleton steel frame sufficiently rigid to withstand 15 the centrifugal force of the bicycle and rider, which may be easily separated into sections for shipment and quickly separated into sections for use.

Another object is to provide a globe having hinged sections which may be swung open from a central intermediate vertical annulus while the rider is riding within the annulus or loop, leaving him fully exposed to view.

25 Other objects will appear from the following description in connection with the accompanying drawings, in which—

Figure 1 is an elevation of an apparatus embodying our invention; Fig. 2 is an elevation of the same showing the hinged sections swung outwardly; Fig. 3 is a top plan view of the apparatus in the open position; Fig. 4 is an elevation of a portion of one of the sections of the frame showing the 35 manner of connecting locking-catches so that they may be disengaged simultaneously; Fig. 5 is an enlarged detail of a portion of the joint between steel angle-irons of the frame, showing the manner of interlocking 40 the meeting frame members; Fig. 6 is an enlarged detail view of one of the locking catches, showing the manner of connecting it to the operating wire; Fig. 7 is an enlarged detail view of the parts of one of 45 the hinges; Fig. 8 is a detail view showing the I-beam joint between the ribs of the loop portion of the frame; and Fig. 9 is an enlarged detail showing the manner of attaching a base or stand to the loop portion 50 of the frame.

The globe comprises four sectional frames 2^a, 2^b, 2^c, 2^d, which are detachably connected by hinges 3 to the central annulus or loop portion, which is composed of the semi-circular skeleton frame members 4^a, 4^b, bolted

together at the top and bottom. The main skeleton framework is composed of steel bars of commercial shapes riveted into a rigid structure. The intermediate annulus or loop comprises semi-circular I-beams 5^a, 5^b, united at top and bottom by connecting straps 6 bolted to each beam in the manner shown in Fig. 7, and cross-connecting channel-iron bars 8. This annulus or loop constitutes the central frame upon which the four swinging spherical section-frames are hung. It is provided with a base or stand formed by bolting angle-iron pieces 9 to the lower part of the I-beams, a portion of the flange being cut away to permit the pieces 60 to be inserted along the web of the beam as shown in Fig. 8. Each of the four hinged section-frame portions is preferably constructed with marginal angle-irons 12, connected by vertical and horizontal channel 65 irons 14. At the middle horizontal or equatorial belt, the abutting flanges of the meeting angle-irons are preferably constructed to form interfitting joints as shown in Fig. 5, and these flanges are then bolted together. 70 The joint 15 between the two portions of the loop frame is also constructed in this manner.

The hinges 16 connecting the section-frames to the loop frame may be constructed 75 of parts 16^a, 16^b, which may be readily separated by removing the hinge-pin 17, in the manner illustrated in Fig. 6. We prefer to provide each part with a plurality of elongated apertures 18, which may be slipped 80 over the heads of rivets or bolts on the frame bar and then securely fastened by means of a single bolt passing through the hole 19.

For the purpose of very securely holding the frame sections together when in the closed position shown in Fig. 1, we secure a plurality of spring-pressed locking catches 20 to the marginal irons of the sector frames, which hook over the abutting flanges of the loop and adjacent section-frames and unite all parts of the globe in an exceedingly rigid structure. In order 95 that the entire number of locking catches may be released simultaneously, we connect them, in the manner shown in Fig. 4, into 100 two or more series by means of flexible wires 22 to operating handles 24. By pulling the handles the latches will be rocked on their pivots, thereby freeing the section-frames 105 from the loop frame so that they may be 110

swung outwardly upon their hinges into the position shown in Fig. 3. Rollers or casters 25 are secured to the lower point or angle of the frames. Braces 27 are pivotally secured to each of the frame portions, and the loop frame is also braced by means of guy cables 28 which are fastened to block and tackle 30. The entire spherical frame is provided with an inner covering of wire 10 mesh 33, forming an even unobstructed concave surface for the wheels of the cycle.

After the operator has entered the globe with his bicycle, the sector frames are securely locked, and he may then ride in circular or spiral paths over the inner reticulated surface. After having attained some speed, the operator may steer his machine into the plane of the loop-portion of the frame, and the spring catches 20 may then 20 be simultaneously released by pulling upon the handles 24, and the four sector-frames may then be swung outwardly into the position shown in Figs. 2 and 3, thus leaving the operator in full unobstructed view.

25 The many advantages possessed by our construction for the purposes set forth will be appreciated by managers and operators of amusement houses, while the structural advantages will be understood by engineers. 30 The entire globe may be readily assembled and braced in position for use, and may also be quickly dismantled for shipment. The central annulus or loop is exceedingly rigid and forms a firm support for the wing sections, and when the latter is swung open into extended position, the widely separated bearings formed by the casters serve to steady the entire structure.

While we have described in detail the particular construction illustrated in the drawings to show an embodiment of our invention, it is evident that many changes may be made therein without departing from the spirit of this invention.

45 We claim:—

1. A reticulated amusement globe comprising a central annulus or loop, and sec-

tions hinged thereto and adapted to be swung outwardly.

2. A reticulated amusement globe comprising a central annulus or loop, and sections hinged thereto and adapted to be swung outwardly, said annulus having a plurality of circular frame members and intersecting cross ribs, formed of shaped beams.

3. A reticulated amusement globe comprising a central annulus or loop, sections hinged thereto and adapted to be swung outwardly, and locking devices adapted to secure said sections to said annulus.

4. A reticulated amusement globe comprising a central annulus or loop, sections hinged thereto and adapted to be swung outwardly, locking devices adapted to secure said sections to said annulus, and means for simultaneously disconnecting said devices.

5. A reticulated amusement globe comprising a central annulus or loop section, swinging sections hinged thereto, supports secured to the lower angle or bottom of said sections, and means for bracing said sections.

6. A reticulated amusement globe comprising a central annulus or loop section, and swinging sections hinged thereto, each of said sections having arcuate vertical and horizontal frame members of shaped beams.

7. A reticulated amusement globe comprising a central annulus or loop section, swinging sections hinged thereto, each of said sections having arcuate vertical and horizontal frame members of shaped beams, and brace-rods pivotally secured to said frame members.

In testimony whereof we have hereunto set our hands in presence of two subscribing witnesses.

HUBERT RICHMOND.
CARL E. BARBER.
